UNITED STATES PATENT OFFICE

2,425,619

BUILDING WALL STRUCTURE

Carl H. Juergens, Milwaukee, Wis.

Application January 2, 1945, Serial No. 571,087

2 Claims. (Cl. 72-47)

1

This invention relates to improvements in an apparatus and method for casting spaced concrete walls.

One of the objects of the invention is to provide a wall structure of plastic material having insulating means, which may form an integral part of the wall after the concrete mixture has hardened.

Another object of the invention is to provide a hollow, interiorly insulated concrete wall provided with transverse bars which tie the wall elements together and furnish means for securing insulating face plates to the interior faces of the wall.

Another object of the invention is to provide for proper temperature and moisture control during the setting of the concrete mixture.

More specifically the invention comprehends two spaced molds with means comprising tie rods for holding the molds in spaced relation, said tie rods being bonded into the molded structure and forming a reinforcing element therefor and in addition projecting at their extremities to provide fastening means for wall facings as well as the outer mold body. In addition the tie rods or bars have means adjacent their ends for removably holding mold plates in position during molding of the wall.

Other objects will more clearly hereinafter appear by reference to the accompanying drawings wherein like characters of reference designate corresponding parts throughout the several views, in which:

Fig. 1 is a top plan view of a section of the assembly, portions of the outer structure being broken away.

Fig. 2 is a side elevation of a section of a mold assembly.

Fig. 3 is a bottom elevation of Fig. 2.

Fig. 4 is a transverse section through the mold assembly showing a concrete wall section molded thereby.

Fig. 5 is an enlarged fragmentary perspective showing details of the insulating sheets and one form of stay rod connection, and

Fig. 6 is an enlarged detail partly in section taken on line 6-6 of Fig. 1.

In molding the hollow wall it is obviously essential that two spaced molds be provided; that these molds be held in alignment and the removable parts be so constructed and arranged as to permit assembly and disassembly without interference. The mold for each of the spaced walls is formed in sections, each mold being formed of substantially identical panels and thus a description of one of the mold sections will be ample to define the nature of the invention and the construction involved. Each mold section assembly, i. e. each mold section assembly for each spaced wall embodies outer panels 1 and inner panels 2,

2

these panels being formed of a suitable plastic material, and the outer panels being flanged outwardly at their marginal edges as indicated at 3. Radial ribs 4 and a vertical medial rib 5 are integrated with this structure to add to its strength and to accommodate one of the fastening elements. Embedded in one of the end and the bottom flange 3 at spaced points are metal inserts 6 including metal cups 7 for retaining the retracted winged head 8 of the flanged lock bolts 9. These flanged headed bolts 9 cooperate with the outer cammed surfaces 10 adjacent the key slots 11 formed in and with the metal inserts located at corresponding spaced positions in the opposite end flange 3 and the top of the adjacent outer panel of the cooperating mold assembly section. The inserts 6 in the vertical medial rib 5 have similar fastenings 15 which engage and lock the ends of the tie rods or plates 16. Slots are provided in the inserts 6 for the passage of the ends of rods 16 adjacent to the outer face of the rib 5. These slots may be partially formed in the medial flange if desired. The tie rods 18 seat in registering slots 19 in the inserts in the end walls so that the abutting flanges are in abutting contact. These tie rods or plates 18 are relatively wide and extend to the outer marginal edges of the end flanges 3 as clearly shown. The tie rods or plates 18 are slotted at 18' to receive wedges 20 which clamp the inner wall or panel 2 at a predetermined position with the outer panel 1. The slots in the tie rods 18 can be of any number and spaced to suit the thickness of walls anticipated.

The inner panel 2 of each mold section has its ends and bottom edges offset inwardly as at 21 to provide supporting surfaces for the edges 21' of the adjacent mold section. It will be noted that the alternate edges or flanges 21' are staggered to provide an overlapping of the joints as shown in Fig. 1. The offset is preferably of a width identical with the thickness of the adjacent cooperating edge of the adjacent panel which is superposed thereon, thus providing a continuous mold wall surface.

Additional tie rods at the top and bottom flanges are connected to the panel 1 in the same manner as the tie rods 18 but function entirely as spacers and retainers for the inner mold panels 2, as distinguished from the tie rods 18 which space and retain the entire mold assemblies in addition to the individual panels. These tie rods are rounded at their shanks as at 22 to facilitate the movement of the concrete mixture in the pouring of the wall and have their ends 23 bent at a point representing the position of the outer face of the inner panel 2 to retain the same in this position. Washers 24 may be utilized in connection with the bent extremity 23 to provide maximum surface and assist in aligning the in-

ner panel 2 with respect to the outer panel 1. The outer ends of the stay rods are flattened at 25 to seat in the slots heretofore mentioned, these outer extremities 25 having key slots 26 through which the flange lock is inserted.

In the construction of the inner and outer panels of the mold sections, it is preferred that the inner panel 2 be formed of a plastic which will assist in the insulation of the wall both as to heat and moisture. While the outer panel 1 is designed to be formed of plastic, suitably reinforced at its flanges and rib portions, nevertheless this outer panel 1 might be made of a suitable light metal. It is intended that in this structure the inner panel 2 shall remain as an inner wall facing while the outer panel will be removable, by virtue of the flange lock bolts and usable in connection with further molding operation.

In connection with the forming of the mold of a plastic the necessity of having the standard steel forms oiled, is eliminated to prevent oxidation incident to the water in the concrete mixture, or to moisture in the atmosphere while such forms are being stored.

It will be apparent that a hollow cast wall such as produced by the use of the instant invention makes possible the use of two separate concrete mixtures. For instance a structure may be cast or molded with the outside facing of a white concrete mixture, while the inside wall structure formed by the inner panels could be formed of cinder concrete. Such a hollow wall provides the vertical air space between the outer and inner vertical panels thereof, with the tie rods forming a reinforcing of the structure, and intermittently between the structures constitutes a satisfactory architectural construction. Further the outer surface of the two spaced walls, which would be exposed by the removal of the outer panels 1 would provide the metal extensions formed by the extremities of the tie rods 16, 18 and 25, which extremities incorporating characteristics of a flanged lock known in the prior art.

From the foregoing it will be obvious to one skilled in the art that I have provided an assembly by means of which spaced walls of concrete or the like can be formed and wherein portions of the structure remain in situ after completion of the molding operation. Due to the fact that the molded structure is formed of a plastic which inherently includes insulating characteristics it will naturally follow that the wall constructed by use of the present invention is vastly improved insofar as heat and moisture insulation is concerned. It is intended that the mold be formed of such a plastic material that it not only will have insulating characteristics but in addition all possibility of oxidation of the mold and mold parts will be avoided. In metal mold structures oxidation is incidental due to the use of water in forming the concrete mixture or to moisture in the atmosphere where such forms are stored.

Since plastic forms may possibly be poor conductors of the heat generated by the setting of concrete mixture, it becomes necessary to compensate for the poorer heat conduction of such materials and this is accomplished by flushing water or air through the space between the wall sections. This space, of course, will also function for the arrangement of electric conduits, piping of water, sewerage, gas, oil and the like into or from the interior of the building and/or

throughout the building. It will be noted that the column of air confined in such space would, per se, be an insulating factor.

The outer panels would preferably be formed of a plastic of a different type or character from the inner panels of the assembly. These overlapping, joined and spaced interior panel sections could be fabricated of some cheap, fibrous materials, like wood or cloth pulp. As previously stated, these inner mold panel sections are to be left in place after the wall structures are completed and materially add to the insulating values of the wall. In some cases, it may be advisable to coat the surfaces of the interior wall mold panels which are to be subjected to moisture of the concrete aggregate or to a flushing stream of water. Such a coating may consist of a film of moisture and water resisting substance.

By the foregoing structure I have provided means for cooling the concrete mixture after the same has been poured into the forms, this cooling being desirable due to heat generated by chemical reaction during the process of curing of the aggregate. This cooling may be accomplished by flushing water through the space between the opposite interior panels or by blasting cool air through such space. The spaced wall formed by my assembly eliminates wall sweating inside of the building, seepage and conduction of tempered air from within the building and seepage and conduction of either cold or heat from outside to the inside of the building.

This structure permits the forming of walls of any shape and dimension or the spacing of the wall sections as desired. In addition different materials may be used for the two spaced walls and a different surfacing or decorating of the walls may be conveniently obtained as heretofore described through the use of the projecting tie rods.

I claim:

1. A building wall structure for incorporation into a hollow concrete wall comprising spaced transverse bars, insulating sheets, means on said bars remote from the ends thereof positioning and permanently securing thereon said insulating sheets in spaced relation, and means in the ends of each bar for removably holding molding plates in position for molding the exterior faces of the wall, said second mentioned means being subsequently available for attaching elements to the outside face of the wall.

2. A hollow wall structure comprising spaced concrete wall elements, transverse, spaced tie bars extending through the wall structure holding the wall elements in spaced relationship, means in the ends of said bars to secure thereto wall facing units, insulating sheets, and means remote from the ends of said bars permanently securing said insulating sheets against the inner faces of the concrete wall elements.
